METHOD OF MAKING PINKING SCISSORS

Edgar M. Lieberman, Jackson County, Mo.

Application March 28, 1949, Serial No. 83,895

6 Claims. (Cl. 76—104)

1

This invention relates to a hand tool in the form of scissors or shears for making zig-zag cuts or pinked edges in cloth and like material, and more particularly to pinking scissors and the method of making same with blades having interfitting, zig-zag serrated or corrugated portions formed by stamping or pressing operation.

Conventional pinking scissors, especially those used in dress making are heavy and expensive. They are usually made by accurately machining the serrated portions of the blade and then lapping the blades in pairs to provide registration of the edges and clearance. Any misuse such as dropping or cutting heavy materials is apt to spring or otherwise alter the required perfect working relation of the blades. Such misuse destroys the usefulness of the scissors and restoration of same can only be accomplished by sending them to the factory for realignment, relapping or replacement.

The objects of the present invention are to provide a pinking scissors construction that is simple, relatively inexpensive, efficient in action, and when dull or sprung by misuse may be sharpened and restored to usefulness by the employment of no better skill and equipment than that possessed by an ordinary scissors grinder; to provide relatively light weight pinking scissors having blades formed from sheet or strip steel and having interfitting zig-zag shearing portions forming opposed cutting edges of desired shape; to provide pinking scissors having interfitting corrugations stamped or pressed into the shearing portion of the blades to form opposed cutting edges which cut on a zig-zag line, said corrugations being spaced from the back edge of the blade so that a reinforcing rib structure is formed eliminating change in the pitch of said corrugations when stressed as by cutting heavy material and at the time of heat treatment; to provide pinking scissors with blades of metal having slight resiliency and shaped to have desired relative hook, twist and ride in the blades; to provide a method and sequence of steps therein for making pinking scissors blades of desired shape and contour by stamping or pressing operations; to provide a method of forming pinking scissors blades in pairs by stamping the blades together in overlapped relation to form interfitting serrations or corrugations therein the overlapping surfaces of the blades being identical; to provide scissors having sharp points so that material can be pierced before being cut; and to provide a method of making pinking scissors quickly and efficiently in mass production.

In accomplishing these and other objects of the present invention, I have provided improved details of structure and sequences of method steps illustrated in the accompanying drawings wherein:

Fig. 1 is a side elevation of a pair of pinking scissors.

2

Fig. 2 is a plan view of the pinking scissors taken at right angles to Fig. 1.

Fig. 3 is an enlarged longitudinal sectional view through the blades and pivot therefor.

5 Fig. 4 is a transverse sectional view through the blades on the line 4—4, Fig. 2, the cutting edges being in shearing position.

Fig. 5 is a transverse sectional view similar to Fig. 4 and showing the blades moved to closed position.

10 Fig. 6 is a plan view of the bottom die member used for forming the pinking scissors blades.

Fig. 7 is a longitudinal sectional view through the bottom die member on the line 7—7, Fig. 6, 15 illustrating a pair of blade blanks in position prior to forming.

Fig. 8 is a longitudinal sectional view through the die block illustrating the position of the scissors blades after forming and punching operations.

20 Fig. 9 is a transverse sectional view through the bottom die block and blanks on the line 9—9, Fig. 7.

Fig. 10 is a transverse sectional view through the die blocks on the line 10—10, Fig. 8.

Referring more in detail to the drawing:

1 designates a pair of pinking scissors constructed in accordance with the present invention and comprising complemental blade members 2 and 3 provided with handle or gripping portions 4 and 5 respectively. The blade members have intermediate hub portions 6 and 7 pivotally connected together as at 8 to operate about an axis 9. The hub portions 6 and 7 are preferably formed in the blades and consist of flat circular plate portions 10 and 11 having peripheral cylindrical walls 12 and 13 respectively. The walls 12 and 13 are coaxial and of such relative size that the inner surface 14 of the wall 13 rotatably engages the outer surface 15 of the wall 12 and operates as a bearing for the blades. The plate portions are spaced apart by a suitable washer 16 engaging the adjacent faces 17 and 18 of the plate portions 10 and 11 respectively said blades being connected by means of a suitable bolt or the like 19 having a head 20 engaging the outer face of the plate portion 11 and a polygonal shaped shank 21 extending through corresponding shaped apertures 22 and 23 in the plate portion 11 and washer 16. The shank 21 terminates in a cylindrical portion 24 extending through an aperture 25 in the plate portion 10 to rotatably mount the plate portion 24 thereon. The end of the cylindrical portion 24 of the shank is threaded for reception of a nut 26 45 engaging the outer face 27 of the plate portion 10 to retain the hubs in assembled operative position. The washer 16 may have parallel side faces or be suitably beveled to impart desired ride to the blades.

50 55 60 Integral with and extending rearwardly from the hub portions are extensions 28 and 29 on the blades 2 and 3 respectively, said extensions pref-

erably being of reduced width and of suitable shape and length to mount the handles 4 and 5 respectively. The handles 4 and 5 may be formed of metal, plastic or other suitable material, molded or otherwise suitably secured to the extensions 28 and 29 to provide a strong, attractive shape and structure of the handle portions. The handles are preferably formed to fit the hand of the user for maximum comfort and can be offset to one side of the line along which the closed blades extend. Obviously the portion of the extensions between the handles and the hubs may have complementary bends to provide the desired offsets of the handles.

The blades 2 and 3 are integral with the hub portions and extend outwardly therefrom substantially opposite to the extensions 28 and 29. Each of the blades 2 and 3 has back edges 30 preferably tangential with the outer periphery of the wall 13 of the hub portion 7 and converging toward the longitudinal axis 31 of the blades at the free ends 32, said back edges preferably terminating in curved portions 33 at the free ends to provide sharp points at the ends 32 and to enhance the appearance of the scissors. The opposite or inner edges 34 of the blades have flat ground faces 35 spaced inwardly from the longitudinal axes of the respective blades as illustrated in Fig. 1 to provide an overlap of the blades when the blades are in closed position, the inner edges 34 of said blades sloping relative to said longitudinal axes to provide greater overlap and width of the blades adjacent the hub portion.

Formed in the blades and arranged substantially transversely of the respective axes 31 are a plurality of corrugations 36 which extend from the inner edges 34 toward the back edges of the blades, said corrugations terminating as at 37 in spaced relation to the back edges 30 to form a rib 38 adjacent said back edges. In the preferred form the pitch or spacing of the corrugations is equal throughout the length of the blades, said corrugations being concentric with the axis 9 of rotation of the blades. The corrugations formed in the blades are so arranged that the overlapping surfaces are identical, the inner surfaces 39 of the blades having matching depressions 40 and elevations 41, thus assuring a perfect fit of the surfaces of said blades into one another. While the corrugations may be of any desired shape, they are preferably formed by stamping or pressing same into the blades whereby oppositely inclined inner faces of each of said corrugations are straight in cross section and terminate in small complementary arcs 42 along the crest 43 and root 44 thereof as shown in Fig. 3. It is preferable that the corrugations be so formed that the lateral crests of adjacent corrugations are uniform or equally spaced relative to the plane of the ribs 38 on the blades.

The blades 2 and 3 are twisted or otherwise formed whereby the planes normal to the inner surfaces of the blades intersect the planes defined by the axes 9 and 31 as shown in Fig. 4, however the normal planes of the respective blades are substantially parallel with the blades in closed position and the angle of said normal plane with the plane defined by the axes 9 and 31 is such that the cutting edges 44 on the respective flat faces 35 engage as shown in Fig. 4 to provide a shearing action on material therebetween, and as said blades are moved to closed position said angle provides clearance between the respective complementary surfaces of said blades as shown in Fig. 5. The material from

which the blades are formed has slight resiliency and said blades are bent to provide what may be termed a hook herein, and the resiliency of said blades tends to force the complementary inner edges thereof together. With this arrangement, when the blades are open as in Fig. 1, intersecting cutting edges of the blades will be in engagement and the free ends will be substantially one over the other and as the blades are moved to closed position the free ends will be in engagement and the portion adjacent the hubs will be spaced as shown in Fig. 3, thereby maintaining engagement of the cutting edges at the point of cut throughout the length of the blades due to the spacing washer 16, the hook, twist and resiliency of the blades. This action or ride of the blades may be changed by using a beveled washer 16 between the hub portions of the blades.

In cutting material, any tendency of the corrugations to be deformed or to change the registration of the corrugations is resisted by the ribs 38. As the scissors are closed, each opposed pair of cutting edges of a cooperating pair of corrugations first meet at the root of one corrugation and close toward its crest diagonally of the general direction in which the shears are pointing and then along the opposite side of the corrugations from the crest diagonally in the opposite direction to the root, thus forming one undulation of the ziz-zag cut. If the blades become sprung or the hook or ride is otherwise reduced, they can be bent easily to increase the hook and the pressure at the intersecting cutting edges. Also when said cutting edges become dull, they can be sharpened by grinding the flat faces 35 as in grinding ordinary scissors.

In making scissors of the type illustrated and described, blanks 45 and 46 are stamped or otherwise suitably cut from sheets or strips of steel having suitable thickness, hardness and other physical characteristics, said blanks being of suitable size and shape to make the blades 2 and 3, the hub portions 6 and 7, and the handle extensions 28 and 29 respectively. The blanks 45 and 46 are placed in overlapping relation as shown in Figs. 7 and 9 and arranged in the cavity 47 of a lower die member 48, the cavity 47 being such as to substantially conform to the outer surfaces of the blade 3 as later described. An upper die member 49 having projections 50 cooperating and substantially corresponding shaped to the cavity 47 and substantially to the outer surface of the blade 2 is moved downwardly to press or stamp the blanks 45 and 46 into a shape corresponding to the space between the respective portions of the cavity 47 and projections 50 when the die members are in closed position as illustrated in Figs. 8 and 10. This operation forms the blades so that the overlapping inner surfaces are identical. While the die members 48 and 49 are in closed position with the blade members therebetween or said blade members are in other suitable fixtures, a punch 51 is moved through suitable die apertures 52 and 53 to punch holes 54 in the hub portions and coaxial with the axis 9. The die members are then separated and the formed blanks removed for finishing operations as later described.

In forming the particular scissors illustrated in Fig. 1, the cavity 47 in the lower die member 48 preferably is provided with a cylindrical recess 55 conforming substantially in shape and size to the outer surface of the hub portions 7. In the particular die cavity illustrated the blank 46 for the blades 3 is on the bottom, therefore a

cavity 56 corresponding in size and shape to the extension 29 is provided in the block 48 and is cut deeper into the blocks by the thickness of the metal of the blanks than the cavity 57 corresponding in size and shape to the extension 28. The relative angular disposition of the cavities 56 and 57 is such that said extension cavities are substantially in the relative position as the handle extensions would assume when the shears are in closed position, that is the longitudinal axes 31 thereof overlie each other.

Extending from the hub cavity and in the direction opposite to the handle extension cavities 56 and 57 is a cavity 58, the side edges 59 and 60 of which are preferably tangential to the larger diameter of the hub cavity 55, said side edges corresponding in shape to the back edges 33 of the blades 2 and 3 respectively. The edges 59 and 60 extend downwardly into the block 48 and terminate in shoulders 61 and 62 of different depths from the face 63 of the die block 48 to provide the desired twist in the blades relative to the axis 9. The width of the shoulders 61 and 62 is substantially the same as the width of the ribs 38 of the blade members, said inner extremities of the shoulders terminating in undercut portions 64 extending downwardly into the block 48 below the lowermost part of the forming portion of the cavity 58. Extending upwardly from the undercut portion 64 and having uniform spacing 65 from the inner edges of the shoulders 61 and 62 are corrugation forming portions 66 of the blocks, the spacing 65 being such as to permit forming the corrugations and the ribs in the blades without fracture of the metal thereof. The corrugation forming portions preferably consist of alternate projections and depressions 67 and 68 respectively of substantially triangular cross section, said projections and depressions being arcuate transversely of the cavities and concentric with the axis 9 of the hub portions, the pitch, size and shape of the projections and depressions being such as to form the outer surface of the corrugations on the blade member 2.

The inner edges of the blanks 45 and 46 preferably coincide with the side edges 69 and 70 respectively of the corrugation forming portions 66 on the die. The upper die member 49 has downwardly projecting male members 71 and 72 having outer edges adapted to substantially engage the side edges 59 and 60 of the cavity 58, said members 71 and 72 being substantially the same width as the shoulders 61 and 62 and of such depth relative to the face 73 of the block 48 as to engage and press a single thickness of the metal of the blank between the lower faces of said members 71 and 72 and the shoulders 61 and 62 respectively, when the die members 48 and 49 are in closed position. The upper die member 49 is provided with undercut portions 74 aligning with the undercut portion of the member 48. The die member also has matching projections and depressions 75 and 76 respectively corresponding in size, shape and pitch with the projections and depressions of the member 48, the projections 75 aligning with the depressions 68 and the depressions 76 aligning with the projections 67. The upper die member is also provided with a cylindrical projection 77 aligning with the recess 55 and with projecting portions 78 adapted to enter the cavities 56 and 57. The relative spacing and arrangement of the cooperating projections and depressions of the respective dies are such that when the dies are closed

the projections and depressions will close on the metal of the blades, a single thickness of metal being between the projections and depressions at the handle extension portions and at the ribs of the blades and two thicknesses of metal being between the hub portions and the corrugation forming portions for the blades.

The projections 67 and 75 and the depressions 68 and 76 are preferably arranged on a slope relative to the faces of the dies to provide the desired twist in the blades. The blanks 45 and 46 are placed in the cavity 47 and the die members closed. Suitable pressure is applied thereto to form the metal as shown, the design preferably being such that there is a controlled spring back when the dies are opened. By pressing the blade members between the dies as described, the contacting surfaces of the hubs and the inner surfaces of the respective corrugations formed on the blades are complementary and the pivotal relation of the blades and the concentric arrangement of the corrugations is assured. The apertures 54 are preferably punched while the blades are held as described.

25 The formed blades are removed from the dies and the apertures in said blades shaped to conform to the shape and size of the portions of the screw shanks on which they fit. The inner edges of the blades are ground to remove interfering portions of the blades and to sharpen the cutting edges thereof. The grinding of the edges also reduces the spacing of the inner edges of the finished blades from the longitudinal axes thereof to provide the desired angle of approach of the cutting edges to the material.

35 The blades may be heat-treated if desired to provide suitable physical characteristics and the handles 4 and 5 molded or otherwise suitably applied to the extensions thereof. The inner faces of the blades are then given a final grinding for sharpening same. The blades are placed with the apertures therein in alignment and with the washer 16 spacing the hub portions thereof. The shank of the bolt is inserted through the apertures and the nut applied and tightened to secure the blades in operative relation. The fact that the hubs, corrugations and apertures are formed in a die, the forming members of which are concentric, obviates the possibility of the blades being eccentric. This fact assures registering of the projections and depressions of the blades and shearing thereby.

40 It is believed that I have provided pinking scissors of light, durable structure and efficient action, and a method of making such pinking scissors by stamping and particularly by stamping said blades in overlapping relation to form corrugations or teeth thereon and control the spring back whereby the inner surfaces of the blades are complementary, which together with the particular arrangement of the blades and the forming of the twist, hook and ride thereof provide a positive shearing action with sufficient clearance and yet have scissors that can be sharpened by a simple grinding of the inner faces of the blades.

45 What I claim and desire to secure by Letters Patent is:

50 1. The method of making pinking scissors which comprises, cutting a pair of flat metal blade blanks, placing said blanks one on the other with the edges of one parallel and offset transversely of the blades from the edges of the other, forming mating portions of the blades the axes of which are coincident and become the

ultimate pivotal axis of the scissors, forming a plurality of corrugations in the overlapped portions only of the blades concentric with the ultimate pivotal axis of said blades, the adjacent faces of the blades being complementary, bending the blades to incline same to a plane normal to the ultimate pivotal axis thereof, removing a portion along the length of each of the overlapped edges to form cutting edges on said blades, and pivotally connecting together the formed 10 blades for movement about the ultimate axis.

2. The method of making pinking scissors which comprises, cutting a pair of flat metal blade blanks, placing said blanks one on the other with the edges of one parallel and offset transversely of the blades from the edges of the other, forming mating portions of the blades the axes of which are coincident and become the ultimate pivotal axis of the scissors, forming a plurality of corrugations in the overlapped portions only of the blades concentric with the ultimate pivotal axis of said blades, the adjacent faces of the blades being complementary, bending the blades to incline the longitudinal axes thereof to the ultimate pivotal axis, said longitudinal axes 25 crossing toward the free ends of the blades, removing a portion along the length of each of the overlapped edges to form cutting edges on said blades, and pivotally connecting together the formed blades for movement in substantially parallel planes about the ultimate axis.

3. The method of making pinking scissors which comprises, cutting a pair of flat metal blade blanks, placing said blanks one on the other with the edges of one parallel and offset transversely of the blades from the edges of the other, forming mating portions of the blades the axes of which are coincident and become the ultimate pivotal axis of the scissors and simultaneously forming a plurality of corrugations in the overlapped portions only of the blades concentric with the ultimate pivotal axis of said blades, the adjacent faces of the blades being complementary, bending the blades to incline same to a plane normal to the ultimate pivotal axis thereof, bending the blades to incline the longitudinal axes thereof to the ultimate pivotal axis, said longitudinal axes crossing toward the free ends of the blades, removing a portion along the length of each of the overlapped edges to form a cutting edge on said blades, and pivotally connecting together the formed blades for movement in substantially parallel planes about the ultimate axis.

4. The method of making pinking scissors which comprises, cutting a pair of flat metal blade blanks, arranging the blanks one on the other with the edges of one parallel to and offset transversely of the blades from the edges of the other, forming cylindrical interfitting members in the blades the axes of which are coincident and become the ultimate pivot axis of the scissors, said cylindrical members having adjacent faces in planes substantially normal to said pivot axis, simultaneously forming a plurality of equally pitched corrugations in the overlapped portions only of the blades from the cylindrical members to the free ends of said blades, said corrugations being concentric with the ultimate pivot axis of said blades and having crests of adjacent corrugations on opposite sides and substantially equally spaced from the plane of the blade blanks, the adjacent faces of the blades being complementary, removing a portion along the

5

length of each of the overlapped edges to form cutting edges on said blades, and pivotally connecting together the formed blades for movement of the blades in substantially parallel planes about the ultimate axis, whereby the cutting edges of the blades are in engagement at their point of intersection and overlapped portions of said blades are in spaced relation.

5. The method of making pinking scissors which comprises, cutting a pair of flat metal blade blanks, arranging the blanks one on the other with the edges of one parallel to and offset transversely of the blades from the edges of the other, forming cylindrical interfitting members in the blanks the axes of which are coincident and become the ultimate pivot axis of the scissors, said cylindrical members having adjacent faces in planes substantially normal to said pivot axis, simultaneously forming a plurality of equally pitched corrugations in the overlapped portions only of the blades from the cylindrical members to the free ends of said blades, said corrugations being concentric with the ultimate pivot axis of said blades and having crests of adjacent corrugations on opposite sides and substantially equally spaced from the plane of the blade blanks, the adjacent faces of the blades being complementary, bending the blades to incline same to a plane normal to the ultimate pivot axis thereof, bending the blades to incline the longitudinal axes thereof to the ultimate pivot axis, said longitudinal axes crossing toward the free ends of the blades, removing a portion along the length of each of the overlapped edges to form cutting edges on said blades, and pivotally connecting together the formed blades with the adjacent faces of the cylindrical interfitting members in aligned spaced relation for movement of the blades in substantially parallel planes about the ultimate axis, whereby the cutting edges of the blades are in engagement at their points of intersection and overlapped portions of said blades are in spaced relation.

6. The method of making pinking scissors which comprises, shaping a pair of incompletely formed metal blades, placing one of said incompletely formed blades on the other in partially overlapped position with the edges of one offset transversely from the edges of the other, forming mating portions of the blades the axes of which are coincident and become the ultimate pivotal axis of the scissors, and simultaneously pressing a plurality of corrugations in the overlapping portions only of the blades whereby the adjacent faces of said blades are complementary, said corrugations being concentric with the ultimate pivotal axis of said blades.
